(57) **CLAIM**

The ornamental design for cover for neck, as shown and described.

DESCRIPTION

FIG. 1 is a front elevational view of a cover for neck showing my new design;

FIG. 2 is a back elevational view thereof;

FIG. 3 is a right side elevational view thereof;

FIG. 4 is a left side elevational view thereof;

FIG. 5 is a top elevational view thereof;

FIG. 6 is a bottom elevational view thereof; and,

FIG. 7 is an in use view of the device.

The broken lines shown in FIG. 7 showing a person illustrate unclaimed environmental matter only and form no part of the claimed design.

1 Claim, 5 Drawing Sheets
